JAMES C. FORRESTER, OF NEW YORK, N. Y.

BOTTLE-CAP-ASSEMBLING MACHINE.

1,131,355.

Specification of Letters Patent.

Patented Mar. 9, 1915.

Application filed June 20, 1913. Serial No. 774,784.

To all whom it may concern:

Be it known that I, JAMES C. FORRESTER, a citizen of the United States of America, and residing at New York, in the county of New York and State of New York, have invented new and useful Improvements in Bottle-Cap-Assembling Machines, of which the following is a specification.

The general objects of my invention are to accomplish in a single machine the automatic assemblage of the complete bottle cap. These bottle caps, as well known in the art, usually consist of a metallic shell or "tin" as it is termed, within which a sealing disk 15 ordinarily known as the "cork" is secured by a suitable adhesive.

My invention contemplates the feeding of the tins, the supplying of adhesive and corks, and the permanent assemblage of the 20 corks in the tins all by automatic means and it is one of the special objects of the invention to secure this automatic assemblage of the caps in a most efficient and rapid manner.

In the carrying out of my invention I propose to feed the tins to the device which brings the parts of the cap together in permanent relation, the "assembling device" as it is called, by means of an endless conveyer 25 which is operated continuously and so serves to feed the tins to the assembling device just as fast as that device is capable of operating. As the adhesive which is usually employed has to be heated before it becomes 30 softened and sticky, my invention contemplates the making of this conveyer as a pair of chains spaced apart to leave an opening therebetween and having a burner to discharge up through this opening to thereby 35 heat the tins on their way to the assembling 40 device.

The fusible adhesive may be placed in the tins before they are heated, while they are being heated or after they are heated and in 45 this connection a special feature of the present disclosure consists in depositing the adhesive in the tins while they are at a point removed from the conveyer and in then placing these tins as fast as they are charged 50 with the adhesive upon the continuously running conveyer by means of an intermittently operating pusher. This pusher is operated at a rate of feed substantially equivalent to the working capacity of the 55 assembling device and by operating the conveyer at a higher rate of feed than this, the

tins are accelerated and fed up to the assembling device at a relatively rapid rate but owing to the timing of the pusher in respect to the assembling device, never more 60 than the needed number of tins will be fed.

The invention furthermore contemplates the automatic supplying of the tins to be taken by the conveyer. The means illustrated for this purpose is an auxiliary conveyer and a special feature of the invention resides in arranging the two conveyers at an angle in respect to each other, disposing the adhesive supplying means at an intermediate station between the two conveyers and utilizing the intermittent pusher as a means for transferring the tins from the auxiliary conveyer to the adhesive supplying means and the tins in advance, from beneath the adhesive supplying means out onto the main 75 conveyer.

Another feature of the invention resides in the arrangement of the driving mechanism of the machine, which in a general way, consists in operating an angularly disposed 80 shaft from the main drive shaft, operating the main conveyer and the pusher from the main shaft and the adhesive supplying means and the auxiliary conveyer from the angularly disposed shaft.

Various other features of the invention will appear as the specification proceeds.

The accompanying drawings illustrate a practical embodiment of the invention but I would have it understood that the invention 90 is susceptible of many changes and modifications.

Figure 1, is a general plan view of a cap assembling machine constructed in accordance with and embodying the invention, certain of the parts being broken away. Fig. 2, is a longitudinal sectional view taken substantially on the line 2--2 of Fig. 1. Fig. 3, is a view of the adhesive supplying means and auxiliary conveyer looking at the left hand end of the machine in Fig. 1. Fig. 4, is a sectional view of the same taken substantially on the line 4--4 of Fig. 1. Fig. 5, is a sectional view taken substantially on the line 5--5 of Fig. 2 showing the assembling turret and sprockets for the main 95 conveyer chains. Fig. 6, is a sectional view of the punch mechanism which cuts the adhesive medium and supplies it to the tins. Fig. 7, is a cross sectional view of the main 100 conveyer, taken substantially on the line 7--7 of Fig. 1. Fig. 8, is an enlarged 105

tional view of one of the assembling punches, taken substantially on the line 8—8 of Fig. 1.

Referring now to the drawings in detail: 5 The numeral 10 designates the assembling device, 11 the main conveyer, 12 the auxiliary conveyer, 13 the adhesive supplying means and 14 the "cork" supplying means. The assembling device is in the form of 10 a turret having a series of assembling punches 15 which are guided between the upper and lower plates 16 and 17 and serve to drive the cork down through the guide passages 18 into the tins 19 seated in the 15 pockets 20 in line with such guide passages. The guide passages 18 and pockets 20 are here formed in a plate 21 fast on the turret shaft 22, below the lower guide plate 17 and the tins when in the pockets are supported upon the bed plate 23 which forms the bottom member of the turret. The turret is rotated with an intermittent step by step movement so as to bring the pockets successively into line with the point at which 25 the tins are supplied, by means of a feed pawl 24 carried by the vibrating lever 25 and held by a spring 26 in engagement with a ratchet 27 on the underside of the bed plate 23. The vibrating lever which actuates the feed pawl is shown mounted on a pivot 28 and operated by a cam 29 on the end of the main drive shaft, the said cam having a cam groove 30 in which engages a roller 31 carried by the end of the lever. 30 The assembling punches are operated in the present instance by springs 32 which force the punches downward, and a relatively stationary cam 33 which serves to lift the punches. The punches carry rolls 34 40 which in the rotation of the turret, ride up the incline of the cam thereby lifting the punches, and the cam terminates abruptly at its highest point 35, as indicated in Fig. 5 so as to suddenly release the punches and 45 permit them to drop down and drive the corks into the tins. The cam may be made with a depression 36 to receive one of the rolls 34' which thus prevents backward rotation of the turret. In addition to this I 50 have shown a dog 37 which drops in behind the ratchet teeth and thus serves to positively lock the turret against backward movement.

The main conveyer in the present disclosure 55 is in the form of a pair of endless conveyer chains 38 spaced apart in parallel relation (see Figs. 5 and 7) to provide an opening 39 therebetween for the burner 40 to discharge up through. The upper runs of the 60 chains extend as shown in Fig. 2 from a point adjacent the adhesive supplying means to a point adjacent the edge of the bed plate 23 of the turret. The chains are driven from the main drive shaft 41 of the machine 65 through the intermediacy of gears 42,

43 and sprocket 44 and the upper runs of the chains are supported practically flush with the surface of the bed 45 of the machine by the two end sprockets 46 and the intermediate guide rolls 47. The lower sides of the 70 chains pass over guide sprockets 48 and over a loose roll 49 which roll keeps the chains from rubbing against the main drive shaft 41.

A guideway is usually provided to direct 75 the tins and prevent them from sliding off the conveyer. This guideway is designated 50 and as shown in Fig. 7 it forms in effect a passageway above the conveyer, with the conveyer forming a bottom to such passageway. In the arrangement illustrated in Fig. 7 this guiding passage is made with an open channel 51 in the bottom of the same to receive the conveyer chains and the burner, and the chains are supported in the channel 85 52 by mounting the chains supporting rolls 47 on the opposite walls 52 which form the two sides to the channel.

The gearing for the conveyer is proportioned to operate the conveyer at a rate of 90 feed greater than the speed at which the assembling device is operating upon the tins. In this way the tins are speeded up on their way to the assembling device. This causes a number of the tins to accumulate just in 95 front of the assembling device, as indicated in Fig. 2, so that just as quick as one of the pockets in the assembling device comes into register with the conveyer, the foremost tin is pushed on into the pocket without any 100 loss of time.

The auxiliary conveyer for supplying the tins to the main conveyer, indicated at 12, is disposed at a right angle to the main conveyer and is arranged to convey the tins 105 from a rotating table 54 or other source of supply to a point adjacent to the end of the main conveyer. This auxiliary conveyer is in the present instance merely an endless belt which passes from a driving pulley 55 110 over two idler pulleys 56 and 57 which as shown in Fig. 3 define the active upper reach of the belt. Driving pulley 55 is carried by an auxiliary drive shaft 58 disposed at a right angle to the main shaft and operated 115 from the main shaft through bevel gears 59 and 60.

The means for supplying the adhesive for sticking the corks in the tins is according to the present disclosure located at a 120 station intermediate of the auxiliary and main conveyer, and substantially at the angle of intersection of the planes of these two angularly disposed conveyers. Also a single intermittently acting device is employed 125 to transfer tins from the auxiliary conveyer to the adhesive supplying means and from this means out onto the main conveyer. The adhesive supplying means is here shown as a punch 61 which strikes 130

disks or collets 62 out of a tape 63 of prepared paper supplied from a roll 64. This paper under the influence of heat becomes soft and sticky. Fig. 4 shows how the 5 punch strikes out a piece of the fusible adhesive medium and by this same action deposits the adhesive medium in the tin then beneath the punch. The punch is usually made with a yielding stripping member 65 10 which first yields as it contacts the strip of paper and then as the paper is cut, forces the cut section out of the die 66 of the punch down into the tin. When beneath the punch the tins rest upon a table 67 which 15 may be a part of the bed 45 of the machine or else be made as a separate part, as shown in Figs. 4 and 6. The feeding of the tape to the punch is here effected by a pair of positively driven friction rolls 68 and 69 20 which are operated from the auxiliary drive shaft through sprocket 70, chain 71, sprocket 72 and a pinion 73 which rotates with said sprocket and engages a gear 74 on the lower feed roll.

25 The punch may be operated in various ways. In the present instance, there is a plunger 75 guided for vertical movement in a standard 76 and connected to the punch by a cross head 77. This plunger is pressed 30 downward by a spring 78 and carries a roller 79 on its lower end bearing upon a cam 80. The cam 80 has a depression 81 therein, into which the roller on the plunger drops and thus causes the punch to descend and strike out a section of the adhesive medium.

The transferring device is indicated at 82 in the form of a pusher carried by a rod 83 which is slidably engaged in bearings 84 40 and is reciprocated by a cam 85 on the main drive shaft, the rod for this purpose carrying a cam roll 86 which bears against said cam and a spring 87 being provided to cause the roll to follow the cam. The 45 pusher is shown provided with an extension or finger 88 which serves as a stop to limit the forward feed of the tins on the auxiliary conveyer and with a pocket 89 to receive and center each tin taken by it. The 50 stroke of this reciprocating pusher is sufficient to carry the foremost tin on the auxiliary conveyer over to a point beneath the adhesive supplying means and the movement thus imparted to this tin causes it to 55 push the tin which has just received a charge of the adhesive, from beneath the adhesive supplying means, out onto the main conveyer. This transferring device operates at a rate of feed substantially 60 equivalent to the rate at which the assembling device is operating upon the tins so that never more than the requisite number of tins will be fed to the assembling device, and the conveyer operating as it does at a 65 higher rate of feed than this advances the

tins faster than they can be taken by the assembling device so that the tins are bunched together in front of the assembling device in readiness to be fed into the pockets just as fast as the pockets are 70 brought into line with the conveyer.

The rotating feed table is shown operated from the auxiliary drive shaft through the medium of a pulley 90 on that shaft, belt 91, and pulley 92 on the shaft 93 which 75 carries the said table, and the tins are conducted from the table onto the auxiliary conveyer through a guide channel 94. Figs. 1 and 3 show how the rotary feed table is disposed at one side of the auxiliary drive 80 shaft and the tape feeding rolls at the other side of the shaft and how these devices are driven from said shaft by driving connections extending in opposite directions from the shaft. This arrangement provides a 85 very compact and efficient form of drive.

The cork supplying means indicated in a general way by the reference numeral 14, here consists of a tube 95 adapted to receive a quantity of the sealing disks or "corks" 90 as they are usually called, and a reciprocating slide 96, which as indicated in Fig. 2 serves to strip the lowermost cork from beneath the tube and push it through the chute 97 out over the guide passage 18. 95 This cork supplying means is operated by the same cam (29) which serves to rotate the turret, the vibrating lever 25 being for the purpose provided with an angular extension or arm 98 having a slotted connection 99 with the slide 96.

To insure a more positive sticking of the corks in the tins, means are usually provided for applying additional pressure to the assembling punches just after they drive the 105 corks into the tins. This means is illustrated in the present instance as a rocking lever 100 pivoted at 101 and having a cam surface 102 arranged to bear down upon the cam rolls 34 of the punches. This pressing device is 110 in the present instance operated also by the cam 29, the vibrating lever 25 being for this purpose supplied with an arm 103 having a slotted connection 104 with the rocking lever 100. The intermittent movements of the 115 turret are cushioned by a yielding stop 105, which as shown in Fig. 5 is carried by the lever 100 in position to be engaged by the cam rolls 34 of the punches. This stop is rocked upwardly to permit the cam roll of 120 the foremost assembling punch to drop off the high point of the cam and then it is rocked in the reverse direction to cause the cam surface 102, to press down upon the top of the cam roll and thereby press the 125 cork which has just been seated in the tin all the more firmly in engagement with the tin.

The full operation of the machine is as follows:—The tins placed upon the rotating 130

- table 54 are fed by this table through the guide channel 94 out onto the auxiliary conveyer 12 and this conveyer carries the tins up to a point at one side of the adhesive supplying means. The pusher then acts to transfer the foremost tin on the auxiliary conveyer over to a point beneath the punch which supplies the adhesive medium and this tin pushes the tin preceding it from beneath the punch out onto the main conveyer. The punch descends and deposits a charge of the adhesive in the tin and the pusher on its next stroke causes the tin next in rear of the tin under consideration to push this adhesive-charged tin from beneath the punch out onto the main conveyer. This conveyer traveling at a relatively high rate of feed picks up the charged tin and feeds it at accelerated speed up into engagement with the tins in advance of it (see Fig. 2). During this travel on the main conveyer the tin is heated by the burner which discharges its heat up between the conveyer chains and the fusible adhesive medium in the tin is thereby softened and made sticky. As the turret turns one step another one of the pockets 20 is brought into line with the main conveyer and this conveyer running continuously as it does acts to push the foremost of the bunched tins off the conveyer and into the pocket. At about this same time the cork supplying means feeds off one of the sealing disks into the top of the guide passage 18 and then as the turret is fed another step the cam roll 34 rides off the peak of the cam 33 and the assembling punch descends and drives the cork into firm engagement with the fused adhesive medium in the tin. The pressing device now acts and by pushing down upon the assembling punch it serves to press the cork all the more firmly and positively to its seat in the tin. The spring-pressed assembling punch holds the assembled cap under pressure during the rotation of the turret and this gives the adhesive an opportunity to "set" and harden. Then when in the rotation of the turret the cam rolls 34 strike the low end 107 of the stationary cam 33, the punches are lifted and the now permanently assembled cap is freed from pressure. The completed caps are now discharged from the assembling turret, such discharge being accomplished in the present instance by a stripper finger 108, which as shown in Figs. 1 and 8 projects into the undercut portion 109 of the pockets and deflects the tins outward so that they fall down through an open 110 in the bed of the machine onto a discharge conveyer 111.
- By the machine of this invention the caps are assembled and permanently united wholly automatically and at a very rapid rate. The terms which I have used in describing the invention are to be understood as terms of description rather than of limitation except as may be required by the prior art. An advantage possessed by my invention over previous machines for this purpose is that the cork is not placed in the tin until after the heated tin has been entirely removed from the heating means. This prevents the corks from being injured by the heat and as the tins cool off more rapidly when separated and removed from the heating means the corks will adhere sooner and hence the pressure employed in assembling does not have to be maintained for so long a time when applied as herein set forth.
- Upon starting the machine the main conveyer is usually first charged or loaded with tins. During this period of charging the conveyer the assembling turret should be rendered inoperative so as not to carry off the tins as fast as they are placed on the conveyer. I have provided a means for this purpose in the illustration in the shape of an eccentric 114, arranged when operated by the handle 115 to throw the turret driving pawl 24 out of engagement with its ratchet 27. The feed of corks during this preliminary charging operation should also be stopped and this I have provided for by a hold-up finger 120 which when swung around its pivot 121 down into its lowermost position serves to support the lowermost cork and prevent feeding of the corks. After the proper number of tins have been fed out onto the main conveyer the turret feeding means and the cork supplying means are rendered operative and the machine commences to operate in the manner described.
- What I claim is:
1. In a bottle cap assembling machine, the combination with an assembling turret provided with pockets in the periphery thereof to receive the tins, a substantially horizontally disposed conveyer passage extending in a straight line to the peripheral portion of the assembling turret, an endless chain conveyer supported in the conveyer passage with the upper run thereof extending up to a point adjacent the periphery of the assembling turret and disposed substantially in the horizontal plane of the pockets in the assembling turret, means for supplying tins to the end of the chain conveyer farthest removed from the assembling turret, means operating said conveyer to carry the tins supplied thereto positively and in a short direct path through the conveyer passage on into the pockets in the turret, means for heating the tins being transported through the conveyer passage, means rotating the turret to bring the pockets therein into line with the line of feed of the conveyer and means arranged to supply corks to the tins after said tins have been transported by the chain conveyer past the heating means.
  2. In a cap assembling machine, the com-

bination of a pair of substantially parallel conveyer chains arranged to support the tins and spaced apart to leave an opening therebetween, a burner discharging up through the space between the chains to heat the tins being conveyed by the chains, means for depositing an adhesive medium in the tins, means for supplying corks to the tins, and an assembling device arranged to operate upon the tins advanced by the conveyer chains.

3. In a cap assembling machine, a guide passage for the tins, a continually operating endless conveyer in the bottom of said guide passage and having an opening therein, a burner discharging up through the opening in the conveyer to thereby heat the tins being transported through the guide passage, means for depositing a fusible adhesive medium in the tins, means for supplying corks to the tins, and an assembling device arranged to operate upon the tins advanced by the conveyer.

4. In a cap assembling machine, a guide-way for the tins provided with a conveyer passage in the bottom thereof, conveyer chains disposed on opposite sides of the conveyer passage leaving an opening therebetween, a burner discharging up through the opening between the conveyer chains to thereby heat the tins being transported by the chains, means for depositing a fusible adhesive medium in the tins, means for supplying corks to the tins, and an assembling device arranged to operate upon the tins advanced by the conveyer chains.

5. In a cap assembling machine, the combination of an assembling device, conveyer chains for forwarding tins to said assembling device, a guide passage over the conveyer chains, means for heating the tins being transported through the guide passage on the conveyer chains, adhesive supplying means adjacent the end of said guide passage, a conveyer arranged to forward tins to the side of the adhesive supplying means farthest removed from the guide passage, and an intermittently operating pusher disposed above said second conveyer, reciprocating in the plane of movement of the conveyer chains and arranged to transfer a tin from the conveyer to a point beneath the adhesive supplying means and to push the tins preceding from beneath the adhesive supplying means into the guide passage onto the conveyer chains.

6. In a cap assembling machine, the combination of an assembling device, a conveyer passage, conveyer chains supported at the opposite sides of the said passage, a burner in said passage discharging upwardly between the chains to thereby heat the tins being transported by said chains, and means for supplying corks to the tins.

65 7. In a cap assembling machine, the com-

bination of an assembling turret provided with assembling punches and with a ratchet for rotating the turret, a pivoted lever, a cam for vibrating said lever, means for conveying tins to the turret, a cork feeding device for supplying corks to the tins, means for applying pressure to the assembling punches, connections between the vibrating lever and the cork feeding device and pressure applying means for operating both said means from the vibrating lever, and a feeding pawl engaging the ratchet of the turret and also operated by the vibrating lever.

8. In a cap assembling machine, a main drive shaft, an angularly disposed supplementary drive shaft operated by the main drive shaft, an endless conveyer driven by the main drive shaft arranged to deliver tins to the turret, a cam on the supplementary drive shaft, adhesive supplying means operated by said cam, a second conveyer operated by the supplementary drive shaft for delivering tins to a point adjacent to the adhesive supplying means, a cam on the main drive shaft, a pusher operated by said cam for transferring tins from the second conveyer to a point beneath the adhesive supplying means and from there onto the first conveyer, a second cam on the main drive shaft, cork supplying means operated by said second cam and turret rotating means also operated by said second cam.

9. In a cap assembling machine, the combination of a main drive shaft, a supplementary drive shaft disposed at an angle to and operated from the main drive shaft, an assembling device operated from the main drive shaft, a main conveyer leading to the assembling device and also operated from the main drive shaft, an auxiliary conveyer disposed at an angle to the main conveyer and operated by the supplementary drive shaft, an adhesive supplying punch operated by the supplementary drive shaft, means for transferring tins from the auxiliary conveyer onto the main conveyer operated from the main drive shaft, means operated from the supplementary drive shaft for supplying a strip of adhesive medium to the punch, and means also operated by the supplementary drive shaft for supplying tins to the auxiliary conveyer.

10. In a cap assembling machine, the combination of conveying means arranged to feed a plurality of tins, means for operating said conveying means, an assembling device arranged to take the tins advanced by the conveying means, means for operating the assembling device, and means for interrupting the operation of the assembling device to prevent said device from taking the tins from the conveying means whereby to cause the conveying means to accumulate a plurality of the tins.

11. In a cap assembling machine, the com-

bination of conveying means arranged to feed a plurality of tins, means for operating said conveying means, an assembling device arranged to take the tins advanced by the 5 conveying means, means for operating the assembling device, means for supplying corks to the tins, means for interrupting the operation of the assembling device to prevent said device from taking the tins from

the conveying means whereby to cause the 10 conveying means to accumulate a plurality of the tins and means for interrupting the supply of the corks.

J. C. FORRESTER.
